CLAIM

The ornamental design for a nasal dilator with multiple spring fingers, as shown and described.

DESCRIPTION

FIG. 1 is a top plan view of a first embodiment of a nasal dilator with multiple spring fingers.

FIG. 2 is a perspective view thereof, where the nasal dilator is in a state of use.

FIG. 3 is a three-quarter perspective view thereof.

FIG. 4 is a top plan view of a second embodiment of a nasal dilator with multiple spring fingers.

FIG. 5 is a perspective view thereof, where the nasal dilator is in a state of use; and,

FIG. 6 is a three-quarter perspective view thereof.

The long dash broken lines showing human facial features are directed to environment and form no part of the claimed design. The short dashed broken lines show portions of the nasal dilator with multiple spring fingers that form no part of the claimed design. The dash dot broken lines represent the boundary of the claimed design and form no part of the claimed design.
